UNITED STATES PATENT OFFICE.

JAMES G. JOHNSON, OF CHICAGO, ILLINOIS.

GARMENT-PRESS.

1,397,635.

Specification of Letters Patent.

Patented Nov. 22, 1921.

Application filed June 28, 1919. Serial No. 307,271.

To all whom it may concern:

Be it known that I, JAMES G. JOHNSON, a citizen of the United States, residing at Chicago, in the county of Cook and State of Illinois, have invented new and useful Improvements in Garment-Presses, of which the following is a specification.

This invention relates to appliances for pressing or smoothing out trousers, and its object is to provide a very simple and efficient appliance for this purpose by the use of which the garment is perfectly smoothed out and pressed and a perfect crease is left the entire length of the garment legs.

The object stated is attained by means of a novel combination and arrangement of parts to be hereinafter described and claimed, and in order that the same may be better understood, reference is had to the accompanying drawing forming a part of this specification.

In the drawing,

Figure 1 is a top plan view of one section of the device;

Fig. 2 is a bottom plan view of the other section;

Fig. 3 is a top plan view of the second-mentioned section;

Fig. 4 is a central longitudinal section 30 of the device;

Figs. 5, 6 and 7 are plan views of certain pads or facing sheets;

Fig. 8 is a cross section of the device, and

Fig. 9 is a perspective view of a special 35 clamping bolt.

Referring specifically to the drawing, the body of the press is composed of two sections 10 and 11, respectively adapted to be positioned in face-to-face relation, with the garment therebetween, so that when the two sections are forced toward each other, the garment is smoothed and pressed. The two sections are similar in shape, and each is made of wall-board or any other light material having slight flexibility.

The section 10 is reinforced by rigid longitudinal strips 12 adjacent to its longitudinal edges, and similar reinforcing strips 13 are provided for the section 11, the latter section also having a central longitudinal reinforcing strip 14. These reinforcing strips are on the outer faces of the sections. Before the strips 13 and 14 are applied, a plate 15, shorter than the section 11, is mounted on the outer face of the latter, on top of which plate the strips 13

and 14 are secured, whereby the latter are spaced at one end from the outer face of the section 11 a distance corresponding to the thickness of the plate 15.

The section 10 is provided with cross bars 16 secured to the strips 12, and the section 11 has cross bars 17 secured to the strips 13 and 14. These cross bars project from the longitudinal edges of the sections 10 and 11, and the cross bars of the respective sections are in alinement. The cross bars 17, at one of the projecting ends thereof, carry clamping bolts 18 which extend through end slots 19 in the corresponding projecting ends 70 of the cross bars 16 and are fitted with wing nuts 20. The bolts 18 are fixed to the cross bars 17 by lock nuts 21, with a washer 22 under the latter. At the other ends of the cross bars 17 are longitudinal slots 23 to receive special clamping bolts 24. Each of these bolts has a squared neck 25 seating in a slot 23 and thus preventing the bolt from turning. Then, a rubber washer 26 is applied, and next a lock nut 27, and after 80 passing the bolt shank through the end slot 19 in the corresponding end of the cross bar 16, a wing nut 28 is applied. The object of the elastic washers 26 is to enable the bolts 24 to be pulled away out of the slots 85 19 to permit the section 10 to be slipped on that side away from the section 11 for separation of the press when the garment is to be inserted or removed. The heads of the bolts 24 are shown at 29. Upon tightening 90 up the wing nuts 20 and 28, the sections 10 and 11 are drawn together to press the garment therebetween in an obvious manner.

At one end of the section 11 is made a recess 30 to accommodate the thicker portion of the garment at the side of the pockets and the crotch, and on the inner face of said section is secured a sheet 31 of blotting paper or other soft absorbent material. This sheet 100 is split as shown at 32 so that this portion may sink into the recess 30. In using the device the section 11 will be at the bottom, and the garment is placed on the sheet 31.

Between the legs of the garment is inserted a pad 33 of blotting paper or similar soft absorbent material. This pad is cut out at 34 forming a recess to accommodate the seat of the garment. This allows spacing for the extra thickness of the garment 110 at the seat on account of seams, pockets, etc., but when a smaller sized garment is to

be pressed, an extra and movable length of pad 35 is provided to fill the fold in the seat. The press is therefore adapted to various sizes of garments.

5 The inner face of the top section 10 has a plain cover sheet 36 of the same material as the sheet 31.

By the structure hereinbefore described the garment is evenly pressed. The smaller 10 end of the section 11 engaging the bottom of the leg portions of the garment, is flexible, this being due to the spacing of the strips 13 and 14 from the section at this point. The section 11 is therefore yieldable to the 15 extra thickness at the cuffs of the trouser legs. The side seams of the legs do not affect the pressure on the garment, as the sections 10 and 11 become slightly bowed toward each other when they are clamped, 20 and an even pressure is exerted over the entire surface of the garment. The absorbent sheets between which the garment lies take up the moisture and dust from the garment after it is sponged and placed in 25 the press.

The longitudinal strips 12, 13 and 14 are rigid and extend throughout the entire length of the press, and they are located directly over the crease of the garment legs.

30 The position of the strips is such that the

pressure is directly on the crease and not on the seam. If the pressure were as great on the seam as on the crease, the impression would show through on the other side of the trouser legs. By placing the pad 33 35 between the garment legs, both legs are pressed separately and a perfect crease the full length of each leg is obtained.

It will be noted that the strip 14 is thicker than the strips 13, and it is recessed to seat 40 the cross bars 17.

The elastic washers 26 also serve to support the bolts 24 during their swinging motion, so that their necks 25 will not drop out of the slots 23. 45

I claim:

A press for trousers, comprising flexible top and bottom sections, rigid laterally spaced strips on the outside of the sections, one of the sections being spaced at one end 50 from the strips on said section, and having its inner face recessed at the opposite end to accommodate a thicker portion of the garment, means for drawing the sections together, and a facing of absorbent material 55 on the inner faces of the sections, the facing over the aforesaid recessed portion of one section extending into the recess.

In testimony whereof I affix my signature.

JAMES G. JOHNSON.
